Attorney

UNITED STATES PATENT OFFICE

VIRGIL M. McCONNELL, OF JAMESTOWN, NEW YORK

WALL FIXTURE

Application filed October 18, 1929. Serial No. 400,558.

This invention relates to an improvement in wall fixtures and more particularly to the method and means for removably joining curtains and draperies thereto.

5 Prior to this invention more attention has been directed toward producing devices by which to removably secure curtain fixtures upon wall brackets than has been directed to providing a simple and commercially practical method of securing curtains or draperies to the fixtures. At the present time no adequate structure has been marketed by which curtains or draperies may be removably mounted upon fixtures without the attendant 10 necessity of finishing the supported edge by hemming or the like.

In the present invention applicant discloses a fixture to which curtains or draperies may be attached without the previous preparation of 20 hemming the unfinished edge of said curtains or draperies and this therefore constitutes the principal object of this invention.

Another object of this invention is the provision of a fixture having double supporting 25 means by which to simultaneously secure curtains and over-drapes.

A further object of this invention is the provision of a fixture of this class having telescoping elements facilitating use upon vary- 30 ingly sized frame openings.

Other and further objects of this invention will appear from a consideration of the following specification when taken in conjunction with the accompanying drawings, and 35 in which

Fig. 1 is a perspective view of one modification of this invention having a curtain mounted thereon;

Fig. 2 is a greatly enlarged vertical sec- 40 tional view taken substantially on the line 2-2 of Figure 1;

Fig. 3 is a fragmentary perspective view showing the fixed or supported rod and the removable curtain securing clip;

Fig. 4 is a perspective view showing the manner in which the elements of the fixture are telescopically engaged with each other; and

Fig. 5 is a vertical sectional view of a modi- 50 fication of this invention showing the method

of separately mounting curtains and over-drapes upon one fixture.

Referring to Figure 1 of the drawing, this invention is shown adapted for use upon a window frame 10. Brackets 12, secured by 55 screws 13 to the face of the frame 10, have projecting outwardly, at right angles thereto, arms 14 which terminate in upturned fingers 15. The fixture, generally indicated by the reference character 16, is formed with 60 slots 18 in the upper edge of the supporting or bent ends 17. The fixture 16 is fitted over the arms 14 of the brackets 12, the finger 15 thereof extending upwardly through the slots 18 to support the fixture in position of use. 65 Inasmuch as the method of securing the curtain or drapery fixtures to the frame brackets as well as the structure of the frame brackets constitute no part of this invention, further description thereof is unnecessary. 70

The fixture 16, as shown in the drawing, is comprised of two separable elements, namely, the supporting channular rod 19 and clip 20. The rod 19 is of sheet metal drawn to channular form, the upper and 75 lower walls 22 thereof being arcuately curved and terminate in inwardly projecting flanges 23, parallel to but spaced from the base wall 24 of the rod. A longitudinally extending slot or opening 25 is created be- 80 tween the flanges 23. It is to be understood that when a non-adjustable fixture of this type is produced, it will terminate at each end in supporting ends 17 by which to secure it to brackets 12. However, since frame 85 openings are of such varying width, it is contemplated to produce fixtures, embodying this invention, with telescoping or adjustable elements by which to span all kinds of openings. An inner or supplemental rod 27, having an over all dimension slightly less than that of the rod 19, is telescopically engaged with said rod, being likewise formed with arcuately curved walls 28 which terminate in flanges 29. The flanges 29 terminates flush with the flanges 23 of the rod 19, the purpose of which will later be set forth. 90 From the foregoing it will be understood that the width of the slot 25 is uniform 100

throughout the length of the combined rods 19 and 27.

The clip element 20 is of channular formation and terminates in ends 31, which correspond in length with the ends 17 of the rod 19. The clip 20 is formed with a flat face 33 which is defined by curved walls 34. The walls 34 are continued inwardly to form shoulders 35. From the shoulder 35, the wall is curved outwardly and again inwardly to produce spring flanges 36. As shown in Figure 3 of the drawing, the clip 20 is comprised of two duplicate elements, one telescopically engaged with the other. The inner clip 38 is shaped to produce shoulders 39 and spring flanges 40. The length of the flanges 40 is such that they terminate flush with the ends of the flanges 36 when the elements 20 and 38 are joined together.

20 The clip 20, the flanges 36 of which are spaced apart approximately the width of the slot 25, is snapped into place upon the rod 19. The flanges 23 of the rod 19 engage the outer faces of the flanges 36 adjacent the shoulders 35. The spring pressure of the flanges 36 cause the clip 20 to be firmly held in place upon said rod. The inner clip 38, through the spring flanges 40, is adapted to engage the flanges 29 of the supplemental rod 27 in a manner identical with that described relative to the clip 20 and rod 19. Although the inner rod and inner clip are inter-engaged, the structure of the outer clip 20 is such that it will also engage the inner rod 27 since the flanges 23 and 29 of said rods together produce the slot 25. Where the inner and outer clips overlap each other, the inner rod 27 receives the spring flanges of the outer clip (see Fig. 4). This, however, does not prevent proper engagement between these members at this point.

The modification shown in Figure 5 is for the purpose of supporting on one fixture curtains and over-drapes, the structure being such that the over-drapes may be removed independently of the curtains. A rod 42, similar to the rod 19, is terminated by inwardly turned flanges 43. A supplemental rod 44 telescopically engaged with the rod 42 is likewise terminated by spaced flanges 46. The flanges 43 and 46 define a longitudinally extending slot 47. Mounted in the slot 47 is an intermediate clip 49, shaped to form spring flanges 50 which terminate in vertically disposed walls 51. A second intermediate clip 53 telescopically engages the clip 49, being formed with spring flanges 54 which terminate in vertical walls 55. The inwardly curved flanges 50 and 54 of the intermediate clips 49 and 53 define a longitudinal slot 57. In the slot 57 and engaged with the flanges 50 of the clip 49 is an outer rail clip 58. This clip is formed with a vertical wall 59, the upper and lower edge of which are inwardly curved to produce

70 spring flanges 60 which engage the spring flanges 50 of the intermediate clip 49. The outer clip 58, as well as the supplemental clip 61 telescopically engaged therewith, is substantially identical with the clips 20 and 38 previously described. It will be noted that the outer clips 58 and 61 are snapped into engagement with the intermediate clips 49 and 53 and that the intermediate clips snap into engagement with the flanges 43 and 46 of the rods 42 and 44.

75 When it is desired to mount curtains or draperies through the use of fixtures made in accordance with this invention, the following steps are to be observed: Brackets 12 are mounted on opposite sides of a frame 10 by screws 13. Two rods 19 and 27 are telescopically joined together and adjusted to move the ends 17 in line with the arms 14 of the brackets. The rods are engaged with the fingers 15 through the openings 18 and are now ready to have mounted and secured thereto, by the clips 20 and 38, a curtain or drape 65. The curtain 65, due to the structure of the fixture upon which it is supported, need not be hemmed or in fact finished in any way along its upper edge. The upper portion of the curtain is doubled back upon itself to form a loop or fold 66. The curtain is placed against the rods 19 and 27, being positioned to locate the doubled portion to completely cover the slot 25 in said rods. Clips 20 and 38 are now adjusted so that they will readily engage, not only the front portion of the rods 19 and 27, but the ends 17 as well. By pressing the clips inwardly against the ends and face of the rods, the spring flanges pass through the slot 25 carrying with them the curtain 65. It will be noted (see Fig. 2) that the curtain is held in engagement with the upper and lower flanges as well as against the inner face of the rod. The shoulders 35 and 39 of the clips 20 and 38 are parallel with and only slightly spaced from the flanges 23 and 29 of the rods 19 and 27 as a result, when said clips are mounted, the fold 66 of the curtain is supported in a substantially vertical position.

100 To mount overdrapes in conjunction with curtains, the structure shown in Figure 5 may be used, although it is practicable to provide two sets of fixtures by which to support both the over-drapes and curtains. The curtain 65 is engaged with the rods 42 and 44 by clamping between said rods and the intermediate clips 49 and 53 in a manner similar to that above described. In this instance the upper walls 51 and 55 of the intermediate clips cause the fold 66 of the curtain to be vertically supported. An over-drape 67 is placed against and covers the slot 57 in the intermediate clips 49 and 53. The rail clips 58 and 61 are snapped into engagement with the intermediate clips thus securing the drape 67 in place. Should it be desired to form an

upper loop or fold 68 in the drape, shoulders on the outer clips support said fold.

Attention is directed to the fact that the above disclosed invention not only eliminates the necessity of hemming curtains or draperies along their upper edges but facilitates their repeated use upon windows of various heights by reason of the fact that the curtain material may be of a considerably greater length than the length of one window and such added length concealed by folds in the upper portion of the curtain. When it is desired to hang a curtain upon a window of greater length one or more of the folds is let down and the curtain, without any work being performed upon it, is adapted to the longer window. A further advantage to be derived from a fixture of this type lies in the fact that a curtain may be mounted with any desired artistic vertical folds and such folds cannot be changed without removing the curtain from the fixture. The fixture and curtain together may be removed from the window frame, or the curtains may be drawn apart and upon releasing will return to their original position.

While only two modifications of this invention have been shown and described, applicant does not intend to be limited thereto since it is obvious to those skilled in the art that other modifications or adaptations may be made without departing from the spirit and scope of the invention as set forth in the hereunto annexed claims.

Having thus set forth my invention what I claim as new and for which I desire protection by Letters Patent is:

1. A fixture for supporting curtains and other hangings comprising a pair of telescoping rods, and extensible means removably engaged with said rods, said means being adapted to support a curtain in frictional engagement with said rods.

2. A fixture for supporting curtains and other hangings comprising telescoping channeled rods, and means removably interlocked with said rods, said means being adapted to support a curtain in frictional engagement with said rods.

3. A fixture for supporting curtains and other hangings comprising telescoping rods, inwardly turned flanges defining channeled openings in said rods, and extensible means removably engaged with said flanges, said means being adapted to support a curtain in frictional engagement with said rods.

4. A fixture for supporting curtains and other hangings comprising telescoping rods, flanges defining longitudinally extending slots in said rods, clips removably interengaging said flanges and adapted to support a curtain in frictional engagement with said rods.

5. A fixture for supporting curtains and other hangings comprising a channeled rod,

flanges defining a longitudinally extending slot in said rod, a clip, angularly disposed flanges on said clip, said clip flanges being adapted to enter said rod and frictionally engage said rod flanges.

6. A fixture for supporting curtains and other hangings comprising telescoping channeled rods, an extensible clip removably mounted on said rods and frictionally engaged with the channel walls thereof, and shoulders formed on said clip, said shoulders being adapted to support the unsecured portion of a curtain mounted in said fixture.

7. A fixture for supporting curtains and other hangings comprising telescoping channeled rods, extensible clips removably engaged with said rods, and means adapted to removably engage said clips whereby to support spaced parallel curtains.

8. A fixture for supporting curtains and other hangings comprising extensible channeled rods, intermediate extensible clips removably engaged with said rods, walls defining longitudinally extending slots in said intermediate clips, outer extensible clips removably engaged with the walls of said slots, said intermediate and outer clips being adapted to support spaced parallel curtains on said rods.

In testimony whereof I have affixed my signature.

VIRGIL M. McCONNELL.
